UNITED STATES PATENT OFFICE.

WILLIAM H. PIKE, JR., OF ORANGE, NEW JERSEY, ASSIGNOR TO PIKE ADDING MACHINE COMPANY, OF ORANGE, NEW JERSEY, A CORPORATION OF NEW JERSEY.

OPERATING DEVICE FOR CALCULATING MACHINES.

No. 904,561.

Specification of Letters Patent.

Patented Nov. 24, 1908.

Application filed March 8, 1905. Serial No. 249,046.

To all whom it may concern:

Be it known that I, WILLIAM H. PIKE, Jr., a citizen of the United States, residing at Orange, Essex county, State of New Jersey, 5 have invented certain new and useful Improvements in Operating Devices for Calculating-Machines, of which the following is a specification.

The present invention is applicable to machines of any character in which an operating shaft is moved by rocking a hand lever or handle.

It is especially adapted for use in connection with calculating machines, although 15 available for use in other machines, and is designed to insure a regular action of the working shaft however abrupt and irregular may be the movement imparted to the handle, and whatever may be the differences in 20 its speed of movement.

A further object of the invention is to provide means whereby when the invention is applied to calculating machines having a special key or operating device, such as a 25 "total" key, which should be fully operated before the hand lever or handle is moved, it will be impossible to move the hand lever during the operation of such special key or to move the latter during a movement of the 30 operating handle.

As before stated, the invention is particularly applicable for use in connection with calculating machines, although many of its features are not limited to such use; and 35 therefore in the accompanying drawings it is illustrated as applied to a machine such as that disclosed in U. S. patent to Pike No. 763,692, granted June 28, 1904.

In the accompanying drawings,—Figure 1 40 is a side elevation of an adding machine having the present invention applied thereto, a portion of the casing of the machine being removed; Fig. 2 is an elevation of a part of the machine, viewed from the opposite side from that shown in Fig. 1, the parts being on an enlarged scale; Fig. 3 is a plan of the parts shown in Fig. 2; Fig. 4 is a sectional view of the parts shown in Figs. 2 and 3, the hand lever or handle and parts connected therewith being in a different position 45 from that illustrated in the other figures; Fig. 5 is a detail view; Fig. 6 is a skeleton or diagrammatic view showing parts of the invention in two positions.

Referring to the drawings, 1 designates 55 the working shaft of the adding machine in connection with which the present invention is illustrated, which shaft is mounted in suitable bearings in the frame of the machine and connected with a counter shaft 2 in such 60 manner that said shafts will always move together. 4, 5 and 6 designate respectively the numeral keys, the "sub-total" key and the "total" key of the adding machine, the construction and function of which are fully 65 set forth in the aforesaid patent No. 763,692, and therefore do not require particular description at this time.

The operating handle 7, which may be of any suitable form, is detachably secured to 70 one end of a shaft 8 suitably mounted in bearings in the main frame 9 and a bracket 10 secured to one side of the main frame. As shown, the shaft 8 is arranged in line 75 with the working shaft 1 of the machine.

The countershaft 2 is mounted in suitable bearings on the main frame and said bracket 10, and to said shaft between its bearing in said bracket and the main frame is secured an arm consisting of two parallel plates 11 80 connected by suitable fastening means. A similarly formed arm, comprising two plates 12, is secured on the shaft 8; and to said arms 11, 12, are, respectively, connected plates 13, 14, to which are secured the ends 85 of a coiled spring 15. Said spring is arranged between a pair of bars 16, 17, each having one end secured rigidly to the members of the arm 12 on the handle shaft 8 and having near their other ends slots 18 through 90 which extend pins projecting laterally from the arm 11 on the countershaft 2.

The working shaft, 1, is provided with an arm 19, which is connected with an arm 20 95 projecting from the countershaft 2 by means of a link 21, the ends of which are pivoted to said arms 19, 20, respectively. The arms 19, 20, are preferably so related to each other and the shafts by which they are carried that when the parts are in normal position and the operating lever or handle 7 is elevated, as shown in Figs. 1, 2 and 3, the pivotal connection 22 between the link 21 and arm 20 will lie substantially in a straight line connecting the axis of the shaft 100 2 with the point of connection, 23, of said link 21 with the arm 19 on the working shaft. That is the arms 19, 20 and inter-

mediate link 21 form a toggle-like connection between the working shaft 1 and countershaft 2, by means of which said shafts are caused to always move together. The speed 5 of rotation of the countershaft, and thereby of the main working shaft 1, is controlled by a dash-pot having a cylinder 25, stationarily mounted on the main frame and having its plunger carried by a cross bar 26, 10 the ends of which are connected by links 27 with arms on the countershaft 2.

It will be seen that when the handle 7 is properly moved, both the countershaft and working shaft will be simultaneously and 15 similarly actuated, power from the handle shaft being transmitted to the countershaft through the spring 15. If, however, the handle is moved forward abruptly and more rapidly than the dash-pot permits the countershaft 2 to rotate, said spring 15 will be stretched and the links 16, 17, will move with the arm 12 and handle shaft relative to the arm 11, on the countershaft, and the latter shaft and working shaft 1 connected 20 therewith will only be moved with the proper speed.

Return movement of the handle is effected by a spring link, connecting the upper end of the arm 12 on the handle shaft 30 with a fixed stud 28 on the main frame, and a spring 29 having its ends connected respectively to the arm 12, below the handle shaft, and to the main frame or base of the machine. As shown said spring link connecting the upper end of the arm 12 with the main frame comprises two concentrically arranged springs 30, 31, the ends of which are connected to plates 32, 33, respectively engaging the arm 12 and the stud 28 40 see Fig. 3. Each of said plates 32, 33 is provided with a reduced portion which extends into the inner smaller spring 31, and acts as a spreader therefor, the outer spring 30 being connected with ears 34, on said 45 plates. The arm 12, being elastically connected at both ends with the main frame, is rapidly returned to its normal position after the handle has been depressed and released from the engaging means hereinafter referred to without jar or strain on any of the parts. To insure a full movement of the handle 7 in either direction a sector or plate 55 is mounted on the handle shaft and provided with a serrated edge with which is adapted to engage a spring impelled dog 36, pivotally mounted on the aforesaid bracket 10 attached to the main frame. To prevent the handle from being returned to its original position, before the working 60 shaft has completed its motion, means are provided for positively holding the handle in its forward, depressed, position, until the desired movement of the working shaft is completed. As shown, this means includes 65 a toggle lever, the members 37, 38 of which

are respectively pivotally connected to the arm 12 on the handle shaft and the frame plate 9 of the machine.

When the handle is moved downwardly into the position shown in Fig. 4, the toggle 70 is adjusted so that its members 37, 38, form a continuous straight line from the point of its connection with the frame plate 9 to its attachment with the arm 12 and the handle is therefore locked in its depressed position until the member 38 of such toggle 75 detent is raised or rocked about its pivotal connection with the main frame. Such releasing of the toggle lock is effected as the countershaft 2 completes its movement by a 80 spring impelled hammer 39 which is normally locked in a rearward position, with its actuating spring 40 under tension, by a hook or catch on a bell crank 41, the lower arm of which extends into the path of a stud or pin 85 42 on the arm 11 of the countershaft. As the countershaft completes its movement, due to the forward swinging of the handle, said stud or pin 42 engages the lower end of the bell crank 41, thereby raising the hook or 90 catch thereon from engagement with the hammer 39, which is drawn suddenly forward by its spring 40 and striking the rear face of a downwardly extending projection 95 43 on the arm 38 of the aforesaid toggle 95 lock, rocks said arm 38 upwardly about its pivot and moves the pivotal connection 44 between the arms 37, 38 of the toggle above the line connecting the ends of said arms with the main frame and arm 12 on the handle shaft, thereby permitting the springs connecting said arm 12 with the main frame to return the handle and parts controlled thereby to their normal positions. The arm 38 of the aforesaid toggle detent is provided 100 with a laterally extending flange 45 which prevents said arm from being moved downwardly beyond the position which is effective for locking the handle, said flange bearing on the upper edge of the arm 37 of the 110 toggle when the parts are in the position shown in Fig. 4. It will thus be seen that in case the handle is moved forward more rapid than the shafts 1, 2, are permitted to move, it will be locked by the toggle 37, 38 115 in its extreme forward position until the desired movements of the shafts 1, 2, have been completed, when it will be automatically released as above described. When the handle is properly moved, that is, depressed with 120 a speed corresponding to that with which the shaft 2 is permitted to turn, the toggle lock will be released at the time the handle reaches its forward position, and therefore such lock will offer no hindrance to the return movement of the handle.

The hammer 39 is returned to its rearward position where it is engaged by the hook or catch on the bell crank 41 by a stud or pin 46, projecting laterally from the bar 125

16 of the connection between the handle shaft arm 12 and countershaft arm 11, said pin engaging in its rearward movement a projection 47 on the hammer.

5 The stud or pin to which the rear plate of the spring 15 is connected and which stud or pin extends through the slots 18 in the bars 16, 17, is not connected rigidly to the arm 11, but extends through suitable slots in the 10 plates composing said arm and one end of each of two buffer springs 48 bears on a roller 49, mounted on said stud between the spring plate 33 and the adjacent plate of the arm 11, the other ends of said buffer springs 15 bearing against rollers 50 near the lower 20 ends of the plates forming the arm 11. After the handle has been pulled forward and locked in its forward position by the aforesaid toggle lock and is then released by the 25 action of the hammer 39, the shock resulting from the sudden return movement of the handle is absorbed by the buffer springs 48, said springs being powerful enough to move the handle shaft to its normal position as the 30 countershaft comes to rest.

As explained in the aforesaid patent No. 763,692, it is important and in fact essential that when either the "sub-total" key 5 or "total" key 6 is being depressed, the handle 35 7 should be positively locked against movement until the "sub-total" or "total" key has been fully depressed. It is equally important that neither of such "sub-total" or "total" keys should be depressed during 40 a movement of the operating lever or handle. The means for accomplishing these results will now be described. 51 designates a shaft which is mounted in suitable bearings in the frame of the machine, and has an arm 52 connected, as described in the aforesaid patent, with the lever 53, which is depressed when either the "sub-total" key 5 or "total" key 6 of the machine is operated. A second arm 54, projecting from the shaft 51 in a 45 direction opposite the arm 52, is connected by a link 55 with an arm 56 on one end of a shaft 57, on the other end of which shaft is secured a cam-shaped detent 58. Said detent 58 is provided at its free end with a laterally projecting flange 59. When either the "sub-total" key 5 or "total" key 6 is moved, through the connections just described, the detent 58 is rocked downwardly into the position shown in dotted lines in 50 Fig. 6. During such movement the flange 59 of such detent extends across the path of a stop 60 secured to the outer face of the bar 16 connecting the arm 12 of the handle shaft with the arm 11 on the countershaft, and 55 thereby it positively prevents the handle being moved during the movement of the "sub-total" key or "total" key. Normally the parts just described occupy the positions shown in Fig. 2, in which the detent 58 is 60 held above the stop 60 and offers no obstruc-

tion to the forward movement of such stop and handle connected therewith. If a forward movement of the handle is commenced the stop 60 is brought beneath the flange 59 of the detent 58 connected with the "sub-total" and "total" keys as shown in Fig. 4, and therefore it is impossible to depress either the "total" or "sub-total" keys during the time that the handle is being moved.

Having thus described the invention, I declare that what I claim is:—

1. The combination with a working shaft, of a countershaft, connections whereby both said shafts move together, an operating handle, and means for transmitting motion from the handle to the countershaft including an elastic member, whereby the countershaft is moved by the handle but not necessarily in unison therewith, substantially as described.

2. The combination with a working shaft, of a countershaft, connections whereby both said shafts move together, an operating handle, means for transmitting movement of the handle to the countershaft, including a coiled spring, whereby the countershaft is moved by the handle but not necessarily in unison therewith, and a speed control device, substantially as described.

3. The combination with a working shaft, of a countershaft, connections whereby both shafts move together, an operating handle, means for transmitting movement of the handle to the countershaft, including a spring, whereby the countershaft is moved by the handle but not necessarily in unison therewith, and means for insuring a complete movement of said shafts at each actuation of the handle, substantially as described.

4. The combination with a working shaft, of a countershaft, connections whereby said shafts move together, an operating handle, means for transmitting movement of the handle to the countershaft, including a coiled spring, whereby the countershaft is moved by the handle, but not necessarily in unison therewith, a sector moving with the handle and having a serrated edge, and a pivotally mounted dog or latch adapted to engage said serrated edge, substantially as and for the purpose described.

5. The combination with a working shaft, of a countershaft, connections whereby both said shafts move together, an operating handle, means for transmitting movement of the handle to the countershaft including an elastic connection, a device for insuring a complete movement of the handle at each actuation, and a speed control device connected with said shafts, whereby the shafts are moved by the handle but not necessarily in unison therewith, substantially as described.

6. The combination with a working shaft, of a countershaft, connections whereby both

shafts move together, an operating handle, means for transmitting movement of the handle to the countershaft, including an elastic connection, whereby the countershaft 5 is moved by the handle but not necessarily in unison therewith, and a dash pot limiting the speed of movement, in both directions, of the parts connected with the working shaft, substantially as described.

10 7. The combination with a working shaft, of a countershaft, connections whereby said shafts move together, an operating handle, means for transmitting movement of the handle to the countershaft including an 15 elastic connection, whereby the countershaft is moved by the handle but not necessarily in unison therewith, and a speed control device comprising a stationary dash pot and a plunger connected with the countershaft, 20 substantially as described.

8. The combination with a working shaft, of a countershaft, connected to move with the working shaft, an operating handle, and an elastic connection between the counter- 25 shaft and an arm supported independently of but moving with the handle, substantially as described.

9. The combination with a working shaft, of a countershaft, connections whereby said 30 shafts move together, an operating handle mounted on an independent shaft, an elastic connection between an arm mounted on the handle shaft, independent of the handle, and the counter shaft, and a speed control de- 35 vice connected with the countershaft, substantially as described.

10. The combination with a working shaft, of a countershaft, connections whereby said shafts move together, an operating handle, 40 and means for transmitting movement of the handle to the countershaft including a spring and two parallel bars, said bars moving with the handle and having slots engaging projections on an arm on the counter- 45 shaft, substantially as described.

11. The combination with a working shaft, of a countershaft, connections whereby said shafts move together, an operating handle, an arm mounted on the same shaft as but in- 50 dependently of the handle, and means for transmitting movement of the handle to the countershaft including a spring connecting said arm on the handle shaft with an arm on the countershaft, and bars connected to said 55 arm on the handle shaft to move therewith and having slots which engage projections on an arm on the countershaft, substantially as described.

12. The combination with a working shaft, 60 of a countershaft, connections whereby said shafts move together, an operating handle, means for transmitting movement of the handle to the countershaft including an elastic connection, and a spring connected with a 65 stationary pin and adapted to return the

handle to normal position, substantially as described.

13. The combination with a working shaft, 70 of a countershaft, connections whereby said shafts move together, an operating handle mounted on an independent shaft arranged beyond one end of the working shaft, an arm on said handle shaft, a spring connecting said arm on the handle shaft with an arm on the countershaft, and a spring connecting 75 said arm on the handle shaft with a stationary pin, substantially as described.

14. The combination with a working shaft, 80 of a countershaft, connections whereby said shafts move together, an operating handle mounted on an independent shaft arranged beyond one end of the working shaft, an arm on said handle shaft, a spring connecting said arm on the handle shaft with an arm on the countershaft, and a spring link 85 connecting said arm on the handle shaft with a stationary pin, and comprising two concentrically arranged springs, substantially as described.

15. The combination with a working shaft, 90 of a countershaft, connections whereby said shafts move together, an operating handle, means for transmitting movement of the handle to the countershaft including an elastic connection whereby the countershaft is 95 moved by the handle but not necessarily in unison therewith, a speed control device connected with the countershaft, and a spring link connecting the handle shaft with a stationary post and comprising two concentrically arranged springs, substantially as 100 described.

16. The combination with a working shaft, 105 of a countershaft, an operating handle, a lever fulcrumed at an intermediate point of its length and adapted to be rocked by the handle, an elastic connection between said lever and the countershaft whereby the latter will be moved by the handle but not necessarily in unison therewith, and coiled 110 springs extending in opposite directions from said lever, and each connected at one end to one arm of the lever and having its other end held stationary, substantially as described.

115 17. The combination with a working shaft, a countershaft, an operating handle, and means for operating the working shaft from the handle but not necessarily in unison therewith, of means for holding the handle in its extreme position until the movement of the working shaft is completed, and means actuated at the completion of movement of the countershaft for releasing the handle, substantially as described.

120 18. The combination with a working shaft, a countershaft, an operating handle, and means for operating the working shaft from the handle but not necessarily in unison therewith, of means for holding the handle 125

in its extreme position until the movement of the working shaft is completed, means actuated at the completion of movement of the countershaft for releasing the handle, and a full motion device arranged to insure the full movement of the handle in each direction, substantially as described.

19. The combination with a working shaft, an operating handle, and means for operating the working shaft from the handle but not necessarily in unison therewith, of locking means for holding the handle in its extreme position, a hammer arranged to strike and release said locking means, a catch for holding the hammer out of action, and means for shifting the catch as the working shaft completes its movement, substantially as described.

20. The combination with a working shaft, an operating handle, and means for operating the working shaft from the handle but not necessarily in unison therewith, of a locking means for holding the handle in its extreme position, a hammer arranged to strike and release said locking means, a catch for holding the hammer out of action, means for shifting the catch as the working shaft completes its movement, and means operated by the handle for restoring the hammer to position and engaging it with the catch, substantially as described.

21. The combination with a working shaft, an operating handle, and means for operating the working shaft from the handle but not necessarily in unison therewith, of a toggle lock having one member adapted to be moved by the handle, whereby said toggle will act to hold the handle at the limit of its movement in one direction, a hammer adapted to release said toggle lock, and means for preventing such action of the hammer until the movement of the working shaft is completed, substantially as described.

22. The combination with a working shaft, an operating handle, and means for operating the working shaft from the handle but not necessarily in unison therewith, of a toggle having one member connected to a relatively stationary frame and its other member connected to be moved by the handle to and from a position in line with the aid member, whereby the toggle is adapted to lock the handle at the limit of its movement in one direction, and means for automatically releasing said toggle lock

as the movement of the working shaft is completed, substantially as described.

23. In an adding machine of the character described, the combination with the series of keys employed in recording and accumulating items, and the operating handle, of a key supplemental to those aforesaid, a stop adapted to be reciprocated at each actuation of the handle, a second stop movable to and from the path of said handle stop, and means controlled by the supplemental key for shifting the second stop.

24. In an adding machine of the character described, the combination with the series of keys employed in recording and accumulating items, and the operating handle, of two special keys 5, 6, a stop connected with the handle, a pivotally mounted stop adapted to swing into and from the path of said handle stop, and means controlled by a movement of either of said special keys for shifting the swinging stop to and from the path of the handle stop.

25. In an adding machine of the character described, the combination with the series of keys employed in recording and accumulating items, and the operating handle, of two special keys 5, 6, a stop connected with the handle, a pivotally mounted stop adapted to swing into and from the path of said handle stop, and means controlled by either of said special keys for moving the swinging stop to and from the path of the handle stop, the parts being so arranged that the handle stop is adapted to prevent movement of either special key while it is being reciprocated.

26. In an adding machine of the character described, the combination with the series of keys employed in recording and accumulating items, and the operating handle, of two special keys 5, 6, two adjustable stops mounted to move in intersecting paths, means for reciprocating one of said stops as the handle is moved, and means connected with the other stop and adapted to move it to and from the path of the handle stop when either of said special keys is actuated.

In testimony whereof I have signed my name to this specification in the presence of two subscribing witnesses.

WILLIAM H. PIKE, JR.
